OPERATOR'S CONSOLE FOR A DATA CONTROL SYSTEM

Jerry N. Broadus, Saratoga, Randall R. Faerber, San
Jose, Howard S. Noel, Cupertino, and Konrad H.
Stokes, Los Gatos, Calif., and Donald C. Union, Hous-
ton, Tex., assignors to International Business Machines
Corporation, Armonk, N.Y., a corporation of New
York

Filed Mar. 28, 1968, Ser. No. 11,184

Term of patent 14 years

Int. Cl. D14—02

U.S. Cl. D26—5

FIG. 1

FIG.2

FIGURE 1 is a front perspective view taken from one side of an operator's console for a data control system embodying our new design, the opposite side being a mirror image of the side shown and the top and rear being plain and unornamented; and

FIGURE 2 is a front perspective view taken from one side of a modified form of an operator's console for a data control system shown in FIGURE 1, the opposite side being a mirror image of the side shown and the top and rear being plain and unornamented.

The broken line showing of indicia in FIGS. 1 and 2 is for purpose of illustration only.

We claim:

The ornamental design for an operator's console for a data control system, substantially as shown and described.
